CORE MOUNTING

Carl E. Meyerhoefer, Brooklyn, N. Y., assignor to
 E. A. Laboratories, Inc., Brooklyn, N. Y., a corporation of New York

Application July 28, 1937, Serial No. 156,250

4 Claims. (Cl. 257—137)

This invention relates to a functionally and structurally improved core mounting, and in its more specific aspects aims to provide a structure of this nature which will be of particular value 5 when employed in connection with heat exchange apparatus wherein fluid under temperature differential is depended upon to heat or cool an enclosure such as the body of a motor vehicle.

It is an object of the invention to furnish a 10 structure of this nature and wherein the entire core or fluid receiving assembly is mounted so that it is cushioned against shocks. As a consequence, the danger of damage to the core with resultant leakage is reduced to a minimum.

15 A further object of the invention is that of furnishing a structure of this character in which the noises incident to the passage of fluid through the core will be minimized in so far as possible. Accordingly, the occupants of the enclosure in 20 which the heat exchange device is positioned will not be subject to annoying and distracting noises incident to this factor.

A still further object is that of providing a 25 mounting which will be cushioned against the transmission of noises, acoustically perceptible vibrations, etc., from the motor, so that difficulties in this connection will also be overcome.

An additional object is that of providing a 30 structure embracing relatively few parts, each individually simple and rugged in construction, these parts being capable of production and use at minimum expense and having a life equal to that of the unit with which they are associated.

With these and other objects in mind, reference is had to the attached sheet of drawings illustrating one practical embodiment of the invention, and in which:

Fig. 1 is a top plan view of a heat exchange unit with certain of the parts broken away to disclose underlying construction; and

Fig. 2 is a rear view of such unit with parts similarly broken away.

In these views, the numeral 5 indicates a core 45 which may include upper and lower header portions connected by a heat exchange structure such as a series of cells, tubes, or otherwise. The headers of the core are coupled to a source of fluid, as, for example, by tubes 6, one of which is conveniently provided adjacent one end of one 50 header, while the other is preferably disposed adjacent the opposite end of the second header.

The core is enclosed within a casing 7, conveniently formed of sheet metal, and which may have applied to its rear face a shroud plate 8. 55 In line with the latter and the heat exchange

structure aforescribed, a fan 9 may be mounted. This fan is secured to the shaft of a motor 10, which may also conveniently drive a blower wheel 11, enclosed within a casing 12. Extending from this casing is a duct 13, through which air distributed by the blower wheel is impelled. The air drawn through the heat exchange core by fan 9 may conveniently strike against a deflector ring 14, which may form a continuation of the forward wall of casing 12. The latter may also be 10 inclined outwardly and rearwardly, so that air moving from the fan is deflected outwardly and then forwardly by ring 14.

Secured to casing 7, preferably by being coupled to plate 8, are mounting brackets 15. These are 15 formed with openings through which the shanks or bolts 16 are extended, for the purpose of securing the structure to a suitable surface. These brackets may also support a mounting member 17 to which the motor 10 is coupled.

20 The foregoing structure—generally stated—is disclosed and described in applications heretofore filed, and, except where indicated in the appended claims, forms no part of the present invention. However, it will be observed that, as shown, the 25 brackets 15 are provided with straps 18, having openings through which tubes 6 project. These 30 openings mount grommets 19, of rubber or similar material, which are in firm contact with the tubes 6. Thus, while these tubes are adequately supported, there will be no danger of objectionable contact occurring between the same and the straps.

Moreover, the shroud plate 8 is coupled to casing 7, preferably by bosses 20, extending rearwardly from the latter, and the outer ends of which are formed with screw-threaded recesses. Screws or bolts 21 have their shanks extended through openings in plate 8 and into these recesses. As a consequence, a contractible structure is furnished which, as it acts against the core assembly, will clamp the latter against movement. The casing 7, being formed of metal, it is apparent that it should not directly contact the core. Thus, as shown, the core should have a width and 45 height less than the corresponding dimensions of the shell and casing.

Moreover, the shroud plate is formed with extensions 22 which project inwardly of such plate and provide transversely extending mounting 50 portions adjacent their inner ends. These mounting portions may each be formed with an opening. Thus, rods or cushions 23, of rubber or similar material, may have their reduced end portions extending through these openings, with 55

their opposite ends bearing against the headers or other suitable portions of the core assembly. The shell or casing 7 is also formed, in its inner face, with a series of projections 24, which may conveniently be integral therewith. Each of these projections receives a collar or sleeve 25, again preferably formed of rubber, and it is thus apparent that the entire core assembly is confined within shell 7 by a structure which acts as a floating suspension. In tightening bolts or screws 21, it is apparent that a sufficiently high degree of pressure will be exerted, so that the cushioning elements clamp the core against side-wise movement. Such movement will further be guarded against incident to the mounting of tubes 6.

In certain instances, collars 25 may be dispensed with, or there may be provided, auxiliary thereto, a rubber strip or channel member 26, mounted upon the inwardly extending flange or projection of shell 7. This strip, or its equivalent, bears against the front face of the core assembly, and either acts as a substitute for the collars or tubes, or may function auxiliary thereto. While any desired number of cushioning elements might be employed, it is preferred that four pairs of the same be utilized. This will provide two collar members and cushions for each of the core headers, and it has been found that such an arrangement of the parts is ideal under commercial conditions. It is, of course, understood that, in lieu of single extensions each supporting two rubber cushioning elements, extensions individual to those elements might readily be employed.

35 Thus, among others, the several objects of the invention as specifically afore noted are achieved. It will be appreciated that numerous changes in construction and re-arrangement of the parts might be resorted to without departing from the 40 spirit of the invention as defined by the claims.

Having thus described the invention, what is claimed is:

1. A mounting for the core of a heat exchange unit and including in combination a shell to enclose said core and comprising sections telescopically disposed with respect to each other, means for retaining said sections against separation, a pair of extended portions forming a part of one of said sections and extending inwardly adjacent the inner edge of said section and parallel to one of the faces of the core, resilient cushioning elements interposed between said portions and the adjacent surfaces of said core, and further resilient cushioning means interposed between the 55 opposite surfaces of said core and that section of the shell which lies adjacent such surfaces.

2. A mounting for the core of a heat exchange

unit and including in combination a shell to enclose said core and comprising sections telescopically disposed with respect to each other, means for retaining said sections against separation, a pair of extended portions forming a part of one of said sections and extending inwardly adjacent the inner edge of said section and parallel to one of the faces of the core, resilient cushioning elements interposed between said portions and the adjacent surfaces of said core, reduced ends forming a part of said elements and extending through the openings of said portions, and further resilient cushioning means interposed between the opposite surfaces of said core and that section of the shell which lies adjacent such surfaces.

3. A mounting for the core of a heat exchange unit and including in combination a shell to enclose said core and comprising sections telescopically disposed with respect to each other, means for retaining said sections against separation, a pair of extended portions forming a part of one of said sections and extending inwardly adjacent the inner edge of said section and parallel to one of the faces of the core, resilient cushioning elements interposed between said portions and the adjacent surfaces of said core, projections forming a part of the other of said shell sections and extending towards the adjacent surfaces of said core, and tubular cushioning elements interposed between said latter section and said core, said projections extending into the bores of said tubular elements.

4. A mounting for the core of a heat exchange unit and including in combination a shell to enclose said core and comprising sections telescopically disposed with respect to each other, means for retaining said sections against separation, a pair of extended portions forming a part of one of said sections and extending inwardly adjacent the inner edge of said section and parallel to one of the faces of the core, said portions being formed with openings, resilient cushioning elements interposed between said portions and the adjacent surfaces of said core, reduced ends forming a part of said elements and extending through the openings of said portions, projections forming a part of the other of said shell sections and extending towards the adjacent surfaces of said core, tubular cushioning elements interposed between said latter section and said core, said projections extending into the bores of said tubular elements, pipes extending from said core, and resilient grommets encircling said 55 pipes and connected to said shell.

CARL E. MEYERHOEFER.
